CLAIM

The ornamental design for alignment system elements of a golf putter, as shown and described.

DESCRIPTION

FIG. 1 is a front perspective view of alignment system elements of a golf putter showing my new design;
FIG. 2 is a left side elevation view;
FIG. 3 is a right side elevation view;
FIG. 4 is a top plan view;
FIG. 5 is a front elevation view;
FIG. 6 is a bottom plan view; and,
FIG. 7 is a rear elevation view.

The broken lines showing a golf putter in the Figures are for environment purposes only, and forms no part of the invention.
